(57) **CLAIM**

The ornamental design for a display screen or portion thereof with icon, as shown and described.

DESCRIPTION

The FIGURE is a front view of a display screen or portion thereof with icon, showing our new design.

The outer perimeter illustrated by a pair of broken lines in the drawings represents a display screen or portion thereof and forms no part of the claimed design. The dot-dashed broken lines define the boundary of the claimed design and form no part of the claimed design.
